Inventor:

Elsworth A. Hawthorne
by George B. Remond, Jr., Mfg.
Hawthorne.

UNITED STATES PATENT OFFICE.

ELLSWORTH A. HAWTHORNE, OF BRIDGEPORT, CONNECTICUT.

LIGHTING APPARATUS.

1,368,722.

Specification of Letters Patent. Patented Feb. 15, 1921.

Application filed March 10, 1917. Serial No. 153,978.

To all whom it may concern:

Be it known that I, ELLSWORTH A. HAWTHORNE, a citizen of the United States, and a resident of Bridgeport, county of Fairfield, and State of Connecticut, have invented an Improvement in Lighting Apparatus, of which the following description, in connection with the accompanying drawings, is a specification, like characters on the drawings representing like parts.

This invention relates to lighting apparatus, and is more especially, though not exclusively, concerned with an electric lamp of the search light type, in which a parabolic or other suitable concave reflector is associated with the electric lamp bulb, there being provided mechanism for focusing the latter with relation to the reflector.

My invention will be best understood by reference to the following description, when taken in connection with the accompanying drawings of one illustrative embodiment thereof, while its scope will be more particularly pointed out in the appended claims.

In the drawings:

Figure 1 is a central, vertical, sectional view of a lighting apparatus embodying my invention;

Fig. 2 is a detail plan of the lamp and its focusing mechanism; and

Fig. 3 is a detail, side elevation of some of the parts shown in Fig. 2.

Referring to the drawings, and to the embodiment of my invention which I have selected for illustration, I have there shown a lighting apparatus comprising a suitable light source 4, herein an incandescent electric bulb associated with an appropriate reflector 5, the latter in the present instance being of the well-known parabolic type. The lamp bulb 4 and its reflector 5 may be, and are herein, mounted within a suitable casing 6 providing a chamber 7 at the rear of the reflector.

The lamp bulb 4 may have a base of any suitable type, but that which is herein selected for illustration is what is known as the "Ediswan" base, comprising a metallic shell 8 provided with two laterally projecting pins 9 adapted for engagement with usual bayonet slots 10 formed in a suitable lamp socket 11. These lamps are commonly made in two types, one intended for a two-wire system and the other for a single wire system, in which one of the lamp terminals

is grounded upon the metallic parts of the lamp casing. The latter of these types is herein shown for the sake of illustration, and is provided with a central terminal 12. 60 The metallic shell 8 constitutes the other lamp terminal.

Into the rear end of the lamp socket 11 is tightly fitted a connector plug 13, having an enlarged portion 14 which extends beyond the rear end of the lamp socket to provide for the attachment thereto of the usual lead wire or wires. In the present instance, a single lead wire 15 extends into the plug, and is connected in a well-known manner, 70 which it will be unnecessary here to describe, with a common form of spring-pressed plug terminal 16, which engages the central terminal 12 of the lamp, and constantly tends to urge the latter in a forward direction and maintain its pins 9 seated in the bayonet slots 10.

In order to provide for the necessary focusing of the lamp bulb 4 with relation to the reflector 5, the latter is herein provided with a rearwardly-extending neck 17 which in the present instance is in the form of a ferrule soldered or otherwise appropriately secured to the reflector. Within this neck or ferrule, the lamp socket 11 is mounted 85 to move axially. To produce this axial movement, I have provided focusing mechanism comprising a rotatable actuating member 18, located externally of the lamp casing at a convenient point where it may 90 be grasped by the user. The rotary motion of the member 18 may be translated into rectilinear movement of the lamp by suitable means, herein a screw 19 attached to the member 18 and having screw-threaded engagement with a nut 20, the latter herein forming a part of a yoke 21 provided with a pair of arms 22 suitably secured to the lamp socket 11.

In the present example, the yoke arms 22 100 are secured to the lamp socket 11 by providing the latter with lateral perforations 23 to receive said arms, the latter extending through said perforations and being clenched over onto the inner side of the 105 socket, as clearly shown in Fig. 1, thus securely uniting the yoke and the lamp socket so that movement of one is accompanied by like movement of the other. This provides a convenient and inexpensive way of communicating motion to the lamp socket, and at the same time provides a convenient way

of connecting the lead wire or wires to the plug 13. Moreover, the latter may be conveniently unfastened and then moved in a rearward direction to withdraw it from the 5 socket, whereupon the plug may be withdrawn in a lateral direction from between the arms 22 for purposes of inspection, repair or replacement.

As a means for holding the yoke 21 10 against rotation and enforcing a forward and backward movement of the lamp bulb when the screw 19 is turned, I have provided the socket 11 with a pair of slots 24 to serve as guideways for the arms 22, which have 15 a sliding fit therein. Thus when the screw 19 is turned in the proper direction, the lamp bulb will be carried forward or backward, as the case may be, and properly adjusted with relation to the reflector 5.

20 The screw 19 may be held against axial movement by any appropriate means, but herein it is provided with a reduced portion 25 passing through and journaled in the rear end of the lamp casing 6, and a 25 shoulder 26 engaging the interior of the lamp casing and preventing outward movement of the screw with relation thereto. Inward movement is prevented by the member 18, which bears against the outer 30 surface of the lamp casing. In the present example, this member 18 is in the form of a hollow shell having an inwardly directed flange 27 encircling a reduced portion 28 of the screw 19 and bearing against a shoulder formed by such reduced portion. The flange is clamped against this shoulder by the head of a screw 29 which is threaded centrally into the screw 19. Thus the member 18 constitutes a convenient handle for 35 turning the screw 19 to effect the focusing of the lamp bulb, and if desired, said handle may be knurled as shown in Figs. 2 and 3 to provide a non-slipping surface for the fingers of the user.

40 Since the lamp bulb herein shown is of the single wire type, its terminal 8 is grounded upon the metallic socket 11, the latter in turn is grounded upon the metallic neck or ferrule 17, and the ferrule is grounded upon the metallic reflector 5, which in 45 turn is in electric connection with the metallic casing 6. Any suitable switching means may be provided, as for example a switch 30, which it will be unnecessary here to describe, since the latter forms no essential part of my present invention, it being understood, however, that the switch is suitably connected with the lamp casing, and with the lead wire 15.

50 While I have herein shown and described one specific embodiment of my invention for illustrative purposes, and have dis-

closed and discussed in detail the construction and arrangement incidental to one specific application thereof, it is to be understood that the invention is limited neither to the mere details or relative arrangement of parts, nor to its specific embodiment herein shown, but that extensively deviations from the illustrated form or embodiment 65 of the invention may be made, without departing from the principles thereof.

Having thus described one form of my invention, what I claim and desire by Letters Patent to procure is:

75 1. In a lighting apparatus, the combination of a lamp, a concave reflector associated therewith, a lamp socket provided with a pair of perforations, and mechanism for focusing said lamp with relation to said reflector, said mechanism comprising a coaxially disposed rotatable actuating member, and means for translating rotary motion of said member into rectilinear movement of said lamp, said means including a yoke having a pair of arms extending lengthwise of the axis and secured in said perforations, and a member in which said arms are slidably non-rotatably guided.

80 2. In a lighting apparatus, the combination of a lamp, a concave reflector associated therewith, a lamp socket provided with a pair of perforations, and mechanism for focusing said lamp with relation to said reflector, said mechanism comprising a coaxially disposed rotatable actuating member, and means for translating rotary motion of said member into rectilinear movement of said lamp, said means including a yoke having a pair of arms extending lengthwise of the axis and transversely thereof through 85 said perforations and clenched over onto the inside of said socket, and a member in which said arms are slidably and non-rotatably guided.

90 3. In a lighting apparatus, the combination of a lamp, a concave reflector associated therewith, a lamp socket provided with a pair of oppositely disposed perforations, and mechanism for focusing said lamp with relation to said reflector, said mechanism comprising a coaxially disposed rotatable actuating screw, and means for translating rotary motion of said screw into rectilinear movement of said lamp, said means including a yoke having a pair of arms extending lengthwise of the axis and having their ends bent transversely and entering and secured in said perforations and means restraining 95 rotary movement of said yoke and arms with 100 a screw.

105 In testimony whereof, I have signed my name to this specification,

ELLSWORTH A. HAWTHORNE,
